UNITED STATES PATENT OFFICE.

NEAL J. CAMPBELL, OF ST. LOUIS, MISSOURI.

RAILWAY CROSSING.

Application filed October 18, 1926. Serial No. 142,323.

My invention relates to improvements in railway crossings, and has for its primary object a railway crossing which is smooth so as to eliminate bumps and which can be readily removed in cases of track repair without destroying the crossing.

A further object is to construct a railway crossing which is composed of sections, the sections being of relatively light weight so that a large crew is not necessary to handle the sections. In fact each section is sufficiently light that it can be handled by one man.

A still further object is to construct a railway crossing which is made up of sections having as their base deformed or corrugated sheet metal plates, the plates being deformed or corrugated in such a manner that they can withstand a great amount of pressure without any appreciable or permanent sag.

A still further object is to construct a railway crossing which is constructed of sections having a corrugated sheet metal base and on which a smooth surface is secured. This surface may be of asphalt or analogous material so as to render the traffic surface of the crossing very smooth.

Heretofore railway crossings were either of the board construction or of heavy metal strips, which require considerable labor to remove when rails were replaced, or when any repair of the track was necessary.

With my improvement, very little physical labor will be necessary to handle the various sections of the crossing and at the same time the crossing will be rigid enough to carry any loads imposed upon it.

My crossing is so constructed that it will not interfere in any manner with the automatic block signals or crossing signals by short circuiting and therefore, is not limited in its use to any particular type of railway crossing.

In the drawings:

Fig. 1 is a cross section illustrating slightly over one-half of my crossing and showing the manner in which the same is placed in position;

Fig. 2 is a top plan view of Fig. 1 with a portion of the surfacing broken away showing the supporting plate;

Fig. 3 is a fragmental cross section of one form of deformation;

Fig. 4 is a similar view showing another view of deformation; and

Fig. 5 is a similar view showing still another form of deformation.

In the construction of my device I employ a plurality of ties 6 on which are secured rails 7. These rails are secured by means of spikes as is well known and the rails are arranged in parallel pairs. 8 represents the ball of the rail and 9 the base flange. Intermediate the parallel rails and resting on the ties 6 is a support 10 which is preferably a wooden beam although, if desired, other material may be used. If a wooden beam is used, angle irons 11 are placed along each of its upper longitudinal edges as illustrated in Fig. 1. The purpose of these angle irons will be explained in detail later.

The crossing is composed of a base 12 which is preferably of sheet metal and relatively thin. This sheet metal is deformed preferably by corrugating, some forms of deformation have been illustrated in Figs. 3, 4 and 5, although I do not desire to limit myself to said specific forms. The object of deforming or corrugating the plate is to add to its strength, that is to enable it to resist bending under heavy loads so that a relatively light material can be used for the base without sacrificing its supporting strength. One end of each of the base plates is provided with a support 13 which is adapted to rest on the base flange 9 and fit underneath the ball 8 of each rail and support that end of the plate adjacent the rail. The other end of the plate is supported on the angle irons 11 in case that a wooden beam is used, or, if a metallic beam is used, on the beam itself. My object in using the angle irons 11 with a wooden beam is to prevent the ends of the plate from mashing down into the beam and causing the center of the crossing to sag.

The base plates, which are intermediate the rail, are preferably provided with an angle iron 14 secured to their upper surface and spaced apart from and parallel to the rail 8 so as to leave a passageway for the flange of the wheel. The base plates, which are located on the outside of the rail, do not have this angle or stop because it is unnecessary since the surface, which is applied on the base, can extend over to the rail whereas

in the sections between the rails, it is essential that a stop, such as the angle iron 14, be employed to keep the surface from creeping over to the rail and interfering with the 5 passage of the wheel flange.

The sections interposed between the rails are separated by means of an insulating bar 15 which is preferably composed of wood. The purpose of this is to insulate or 10 separate the base sections 12. This is essential when a block system or an automatic crossing signal for railroads is used so as to prevent short circuiting of the rails.

Located on the base plates 12 is a surface 15 16 which is of any self-hardening material, preferably asphalt, although other surfaces may be used. However a surface, which is 20 pliable, is preferable because there is always a certain amount of spring in the base plates when a vehicle passes thereover. The surface 16 may be either molded directly on the base plate or it may be pre-cast and secured thereon in any well known manner. The space formed between adjacent sections 25 between the tracks, which is occasioned by the insulating strip 15, may be left open or it may be filled with pitch or other material, or if desired the insulating strip may extend completely up to the road surface. The ends 30 of the section removed from the rails are secured in any well known manner as for instance, by means of spikes 17 where a wooden support is used, and by means of bolts or screws where a metallic support is 35 used. I do not however desire to limit myself to any particular means for securing these ends because, as by wedging them in tightly, it may be possible to eliminate the securing means altogether. The ends of the 40 sections on the outside of the rails may be either constructed in the manner illustrated in Fig. 1 or the base plate only may be inserted and the road surface carried thereover completely to the rail without departing 45 from the spirit of my invention. Where securing means for the sections, such as illustrated in Fig. 1 are used, it is preferable to place washers 18 underneath the heads of the bolts or spikes to prevent them from working 50 down through the surface especially when asphalt is used thereby preventing the raising up of the ends. However it is my opinion that by wedging these plates sufficiently tight, that is by having their meeting edges up-tilted and using pressure to force 55 them in place, the fastening means can be dispensed with.

The essential feature of my device is a 60 railway crossing having a deformed or corrugated sheet metal base bridging the space between the rails so arranged as to present a smooth crossing surface and which base 65 has its ends adjacent the rail provided with a support which rests on the base flange of the rail and which contacts with the under-

neath surface of the ball of the rail so that that portion of the crossing adjacent the rail will move up and down with the up and down movement of the rail.

Heretofore with the ordinary crossings it 70 frequently happened that the base flange of the rail would mash its way down into the tie and thus sink below the road surface, leaving a bump, or otherwise the road surface would sink and leave the rail projecting 75 above it. By my construction, however, this is eliminated because there is no possibility of the road surface sinking, nor is there any possible chance of the rail moving up and down without carrying the edge of 80 the crossing adjacent the rail up and down with it.

I may, if desired, eliminate the surfacing material from the plates without departing from the spirit of my invention as it may be 85 desirable for economy's sake, or where the crossing is used on gravel roads, to eliminate the surfacing.

Having fully described my invention, what I claim is:

1. A railway crossing comprising a plurality of corrugated sheet metal plates, means for supporting one end of said plates between the base flange and underside of the ball of a rail, and means parallel to said rail for supporting the opposite end of said plates.

2. A railway crossing comprising a corrugated sheet metal plate, and having one end thereof supported between the base flange and underside of the ball of a rail, means for supporting the opposite end of said plate, and surfacing material located on said plate.

3. A railway crossing comprising a corrugated plate, having a downturned end located between and contacting with the base flange and underside of the ball of a rail for supporting said plate, means parallel to said rail for supporting the opposite end of said plate, and surfacing material covering a predetermined portion of the top surface of said plate.

4. A railway crossing comprising corrugated sheet metal plates provided with an integral support for one end of said plates and fitting snugly between the base flange and underside of the ball of a rail, means for supporting the opposite end of said plates, and means for securing the last mentioned end to said supporting means.

5. A railway crossing comprising a corrugated sheet metal plate, a support integral with one end of said plate and being downturned and adapted to contact with the underside of the ball of a rail and the upper side of its base flange, and means for supporting the opposite end of said plate.

6. A railway crossing comprising a corrugated sheet metal plate, an integral support

- formed on one end of said plate by bending said end downward, said support adapted to be forced between the underside of the ball of a rail and its base flange for supporting 5 said plate and causing it to move up and down with said rail, means for supporting the opposite end of said plate, and means for securing said last mentioned end to its support.
- 10 7. A railway crossing comprising a deformed sheet metal plate, a support formed on one end of said plate and adapted to extend from the underside of the ball of a rail to its base flange, means for supporting 15 the opposite end of said plate, and sur-
- facing material located on the upper surface of said plate.
8. A railway crossing comprising a sheet metal plate having stiffening ribs formed therein, a support carried by one end of said plate and adapted to extend from the underside of the ball of a rail to its base flange, means for supporting the opposite end of said plate, means for securing said last mentioned end to said support, and 20 surfacing material covering a predetermined portion of the top surface of said plate.
- In testimony whereof I have affixed my signature.

NEAL J. CAMPBELL.
